WILLIAM C. O'BRIEN, OF BALTIMORE, MARYLAND

STARTER FOR ELECTRIC MOTORS

Application filed May 17, 1927, Serial No. 192,020. Renewed March 15, 1930.

This invention relates to automatic motor starters for electric motors. The purpose of the invention is to provide a starter in which a single magnet operates a main contactor to close the motor circuits and then operates an armature, provided with retarding means, to close one or more auxiliary contactors which cut the resistance out of the armature circuit of the motor.

10 In carrying out the invention, I provide a magnet having a core extended outside of its coil and an armature hinged to the core and forming an extension of the same, this armature adapted to swing toward and from the pole-piece of the magnet. I also provide a main contactor, of non-magnetizable metal, which is preferably hinged to swing about the same axis as the armature, and this contactor extends between the armature and the 20 pole-piece. Upon the contactor, on the side facing the pole-piece, I provide a magnetizable plate which is adapted to engage the pole-piece, but is held out of actual contact with the armature by the body of the main contactor. The magnetic circuit of the magnet extends through the armature and through said plate to the pole-piece. The armature and main contactor are normally held away from the pole-piece by gravity, and when the 30 magnet is energized, the main contactor is immediately drawn toward the pole-piece and closes the circuits through the motor, the magnetizable plate on the contactor adhering to the pole-piece and forming a cap on the same. This movement of the plate toward the pole-piece does not weaken the magnetic circuit through the armature, but, in effect, builds up the pole-piece, bringing it nearer 40 to the armature. The armature is strongly attracted by the pole-piece but its movement toward the same is retarded by any suitable means, and as it moves toward the pole-piece, it closes one or more auxiliary contactors 45 which cut the resistance out of the armature circuit of the motor. When the magnet is de-energized, the armature and main contactor both fall away from the pole-piece by gravity, assisted by the resilience of the contactors, and the motor circuits are thereby

opened and the resistance is included in the armature circuit.

In the accompanying drawing,

Fig. 1 is a front elevation of the starter, with the parts in normal positions; 55

Fig. 2 is a side elevation of the same;

Fig. 3 is a top plan view of the same;

Fig. 4 is a section on the line 4—4 of Fig. 1, the main contactor being shown in closed position in full lines and in open position in dotted lines;

Fig. 5 is a side elevation of one of the auxiliary contactors; and,

Fig. 6 is a circuit diagram of the starter.

Referring to the drawing, *a* represents a 65 suitable base of insulating material, upon which the starter is mounted, *b* indicates the magnet, *c* indicates the armature for operating the auxiliary contactors, *d* indicates the main contactor, and *e*, *e'*, *e*² and *e*³ indicate 70 auxiliary contactors.

The core of the magnet is secured to an iron frame 1, having integral posts 2 and 3 which project upwardly at one side of the coil 4, this frame constituting an extension 75 of the magnet core. A pin 5 extends through these posts, and the armature *c* and contactor *d* are pivotally mounted upon this pin. The armature *c* has lugs 6 at its lower end which fit closely against the post 2, and the shaft 5 80 extends through these lugs. The armature therefore forms a continuation of the magnet frame. This armature is adapted to swing toward and from the pole-piece 7 of the magnet. A dashpot *f* retards its movement toward the pole-piece but permits the armature to move freely in the opposite direction. As shown, the dashpot comprises a cylinder 8, pivotally connected to a bracket 9 of non-magnetic material, which is secured to the 85 posts 2 and 3 of the magnet frame, and a plunger 10, connected by a rod 11 to a fork 12^a which projects from a non-magnetic cross-piece 12, secured to the back of the armature *c* at its upper end. The function of the armature *c* is to operate the auxiliary contactors to cut resistance out of the armature circuit of the motor, as hereinafter described.

The main contactor *d*, the function of which is to open and close the motor circuits, 100

comprises the arm 13, composed of non-magnetic metal, such as brass, which arm is pivoted upon the pin 5, and a relatively thin iron plate 14, which is secured to the arm 13 opposite the pole-piece 7 of the magnet. When the main contactor swings toward the magnet, the iron plate 14 may engage the pole-piece 7, but it is to be noted that this iron plate or armature is spaced from the armature *c* by the thickness of the switch arm 13, which latter normally lies against the armature *c*, between said armature and the pole-piece of the magnet. The arm 13 carries a yielding contact member 15, adapted to engage a stationary line contact 16, which is associated with a blow-out magnet 17.

The cross-piece 12 projects at both sides of the armature *c*, and is provided with adjustable stops 18, 19, 20 and 21, adapted to engage the auxiliary contactors *e*, *e'*, *e*² and *e*³, respectively. As shown in Figs. 2 and 5, each auxiliary contactor comprises a rectangular frame 22, one side of which is composed in part of a spring 23, and this frame carries arms 24, which are pivotally mounted upon a pin or shaft 25, supported upon the base *a*. A contact 26 on the frame 22 is adapted to engage a stationary contact 27, connected with the resistance of the starter. When the armature *c* is moved toward the magnet, the adjustable stops 18, 19, 20 and 21 bear successively upon the springs 23 of the auxiliary contactors *e*, *e'*, *e*² and *e*³, respectively, and these contactors are moved to closed position in succession, and are held firmly in these positions by the pressure of the stops against the springs. When the armature *c* returns to its normal position, the auxiliary contactors are released and fall by gravity to their open positions. For starting small motors only one auxiliary contactor may be necessary, while for larger motors, the number of contactors may be increased to any desired extent.

In Fig. 6, a circuit diagram of the starter is shown. In this diagram, the line circuit is indicated at *L*, *L'*, and a shunt motor is indicated at *m*. A conductor 28 leads from the side *L* of the supply circuit to the field winding 29 and armature 30 of the motor. The armature circuit proceeds from the armature by conductor 31 to the starting resistance 32, and thence by conductor 33 and connection 34 to the main contactor *d*, and from the stationary contact 16 through the coil of blow-out magnet 17 to the side *L'* of the supply circuit. The auxiliary contactors are all connected to the conductor 33 by connections 35, as shown, and their stationary contacts 27 are connected to the successive sections of the resistance 32, in the usual manner. The field coil 29 of the motor is connected by conductor 36 to the main contactor *d*. It will be evident from an inspection of the diagram that when the main contactor is closed, the

circuits through the field and armature of the motor will be completed, the latter circuit including all of the resistances, and that the closing of the auxiliary contactors in succession will cut the sections of resistance out of the armature circuit, in succession. The circuit for the operating magnet *b* extends from conductor 28 by conductor 37 to the magnet coil, and thence by conductor 38 through a manually operable switch 39 to the side *L'* of the supply circuit. When the switch 39 is closed, the magnet is energized and when this switch is opened, the magnet is de-energized.

The operation is as follows: Normally, the parts are in the position shown in Figs. 1-3, inclusive. When the operator desires to start the motor, he closes the switch 39 and the magnet *b* thereby becomes energized. This causes the attraction of the iron plate or armature, affixed to the arm 13 of the main contactor *d*, and said arm instantly moves toward the magnet and closes the motor circuits between the contacts 15 and 16, as indicated in full lines in Fig. 4. The armature *c* is also attracted by the magnet, but the movement of this armature is retarded by the dashpot *f* and this armature moves slowly toward the magnet, the stops on the cross arm 12 closing the auxiliary contactors in succession, thereby gradually cutting the resistance out of the armature circuit. When it is desired to stop the motor, the operator opens the switch 39, thereby causing the magnet *b* to become de-energized, and the armature *c* and contactor *d* fall back to their normal positions, thereby opening the motor circuits and including the resistance in the armature circuit.

It is to be noted that the air gap between the armature *c* and the pole of the magnet is not changed by the movement of the contactor from its open to its closed position. The magnetic circuit is completed from the magnet frame through the armature *c*, which constitutes an extension of said frame, and through the iron plate or armature 14, which is interposed between the armature *c* and the pole-piece. If the plate 14 directly engaged the armature *c*, it would adhere thereto and the main contactor would not move to closed position independently of the armature *c*, but as the plate 14 is spaced from the armature *c* and is not connected to the magnet frame, the plate can move, with the main contactor, into engagement with the pole-piece, independently of the movement of the armature *c*.

What I claim is:

1. In a motor starter, an electromagnet having a pole-piece, an armature movable toward and from said pole-piece, a main contactor of non-magnetizable metal between said armature and pole-piece and movable independently of the armature, said contactor having a magnetizable part interposed between the armature and pole-piece and spaced from the armature and adapted to engage the

pole-piece, means for retarding the movement of the armature toward the pole-piece, and an auxiliary contactor controlled by said armature.

5 2. In a motor starter, an electro-magnet having a pole-piece, an armature hinged at one end of the magnet core and forming a continuation of the same, a main contactor of non-magnetizable metal, movable independently of said armature and having a plate of magnetizable metal interposed between said armature and said pole-piece and mechanically held out of engagement with the armature, means for retarding the movement of the 10 armature toward the pole-piece, and an auxiliary contactor controlled by said armature.

15 3. In a motor starter, an electro-magnet having a pole-piece, an armature hinged at one end of the magnet core and forming a continuation of the same, a main contactor of non-magnetizable metal hinged to rock about the axis of the armature and extending between said armature and pole-piece and having on its side adjacent the pole-piece a plate 20 of magnetizable metal spaced from said core, means for retarding the movement of the armature toward the pole-piece, and an auxiliary contactor controlled by said armature.

25 In testimony whereof I hereunto affix my
30 signature.

WILLIAM C. O'BRIEN.
